AUTOMATIC MEANS FOR OPERATING CASEMENT WINDOWS AND THE LIKE

Ralph W. Carnahan, near Dayton, Ohio, assignor to The S. H. Thomson Manufacturing Company, Dayton, Ohio, a corporation of Ohio

Application June 26, 1935, Serial No. 28,548

6 Claims. (Cl. 268—117)

This invention relates to new and useful improvements in operating means for casement windows and the like.

It is one of the principal objects of my invention to provide remote control means to open and close casement windows, either singly or in groups.

It is another object of my invention to provide locking means associated with the operating means, to unlock the window before it opens and to lock the window after it is closed.

It is still another important object of my invention to provide automatic means to interrupt the operation of the device when the window is fully opened, or fully closed and locked.

Another important object of my invention is the incorporation of means whereby the window may be partially opened or partially closed without necessitating a full movement in either direction; in other words, the direction of movement of the window may be reversed at will.

In my device about to be described I have provided an automatic operator concealed below the window stool and accessible for repair and adjustment by the removal of either the window stool or apron. Furthermore my invention does not require a radical departure from the customary architectural treatment or sound construction.

I have also incorporated in my device manual means whereby the window operator may be disconnected, and the window opened and closed by hand.

Other important and incidental objects of my invention will be set forth in the following specification and the claims annexed thereto.

In the accompanying drawings, illustrating my invention, Figure 1 is an interior view of a conventional metal casement window, showing my operator attached thereto. Figure 2 is a cross sectional view taken through the window shown in Figure 1. Figure 3 is a vertical sectional view taken through the operator mechanism on the center line of the quadrant shaft. Figure 4 is a cross-sectional view taken on the line 4—4 in Figure 3. Figure 5 is also a sectional view taken on the line 5—5 of Figure 3. Figure 6 is an enlarged detail view of the contactor switch. Figure 7 is a vertical sectional view taken on the line 7—7 of Figure 3. Figure 8 is a detail view of the quadrant drive collars. Figure 9 is a detail view of the locking mechanism positioned upon a mullion or at the window jamb. Figure 10 is a detail view of the remote control switch. And

Figure 11 is a circuit diagram employed with my device.

Referring now to the accompanying drawings for a detailed description of my invention, the numeral 1 indicates a conventional out-swinging 5 steel casement, having a stationary frame 2. On the inside of the window I have shown the conventional window stool 3 and apron 4.

Welded to the sill member 5 of the frame 2, slightly above the stool 3 and projecting inwardly therefrom, is a shelf bracket 6. (See Figures 1, 2 and 3). Secured to the lower face of the bracket 6 by screws 7, 7, is an operator housing 8. This housing is essentially a square case 9 having an open lower face 10. Projecting upwardly from the top of the housing is a ribbed shank or boss 11 having oppositely disposed ears 12, 12 in which the screws 7, 7 are received.

Extending axially of the boss 11 is a quadrant shaft 13 that projects upwardly through the 20 bracket 6. Secured to the upper face of the latter is a housing 14 formed with an elongated opening 15 in its outer face and in alignment with a similar opening 16 in the sill member 5. (See Figure 3).

Positioned within the opening 15 of the housing 14, and projecting through the opening 16, is an operator arm 17 having formed in its inner end a square aperture 18. Within the latter a square shoulder formed on the shaft 13 is received, and where the latter projects through the housing 14, I have secured thereto a handle 20 for manual operation. (See Figure 3).

Attached to the outer free end of the arm 17 is a shouldered stud 21 that is slidably received within an inverted channel guide 22 secured to the lower face of the sill member of the casement 1. When the shaft 13 is rotated, the arm 17 will swing outwardly from the sill member 5 to open the casement, and when moved in the opposite 40 direction, it will cause the casement 1 to close. (See Figures 2 and 3).

The shaft 13 projects into the housing 8 where it is formed with an elongated shoulder 23 of reduced diameter. Rotatably mounted upon this 45 shoulder 23 is a gear quadrant sleeve 24 having at its upper end a square shoulder 25 to which a gear quadrant 26 is attached. Between the quadrant 26 and the lower end of the sleeve 24, I have provided on the latter a shoulder 27 upon 50 which there is freely mounted a locking pawl 28, later to be described. (See Figures 3 and 8).

Formed on the lower face of the sleeve 24 are three equally spaced square teeth 29, adapted to engage similar teeth 30 on the adjacent end of 55

a quadrant shaft drive sleeve 31. This sleeve 31 is also positioned upon the shoulder 23 and to which it is slidably keyed. (See Figures 3 and 8).

Surrounding the sleeves 24 and 31 is a helical spring 32 whose one end is secured to the sleeve 24 by a screw 33 and whose lower end is secured to the sleeve 31 by a screw 34. Now, as shown in Figure 8, the spring 32, which is wound left hand, is attached to the respective collars under tension to hold the teeth 29 and 30 firmly together. When the sleeve 24 is rotated to the right, as viewed in Figure 8, there will be a positive drive connection between the gear quadrant sleeve 24 and the shaft 13. However, when the sleeve 24 is rotated to the left, as viewed in Figure 8, the shaft 13 will be rotated entirely by the tension of the spring 32. The purpose of this yieldable drive in one direction will be hereinafter described.

Projecting horizontally of the housing 8, and in the plane of the frame 2, is a quadrant drive shaft 35, whose ends are journaled in suitable bearings 36 and 37 mounted in the end walls of the housing 8.

Secured upon the shaft 35 is a worm 38 meshing with the gear quadrant 26 and by which it is driven. Also secured upon the shaft 35 is a worm gear 39 meshing with a worm 40 keyed to an intermediate shaft 41 positioned at right angles with the shaft 35. The shaft 41, like the shaft 35, is suitably journaled in bearings 42 and 43 mounted in the walls of the housing 8.

Also keyed to the shaft 41 is a worm gear 44 that meshes with a worm 45 on the shaft of an electric motor 46 by which the device is operated.

The lower face 10 of the housing 8 is adapted to be closed by a cover plate 47 attached to the former by screws 48 and having formed at one corner thereof a circular disc-like projection 49 to receive thereon the motor 46, with the shaft 40 of the latter positioned vertically.

It is obvious that the speed reduction will be high and, when the motor, which is reversible, is rotated in one direction, the shaft 13 will be slowly rotated to open the window; and when the motor is reversed, the shaft 13 will be slowly rotated in the opposite direction to close the window. (See Figures 3, 4 and 7).

Means for limiting the rotation of the shaft 13 will now be described. Secured to the periphery of the sleeve 24 by screws 50, 50 is a depending arm 51, whose lower end terminates in a circular disc 52 formed with a central aperture 53. Riveted in the aperture 53 is the shouldered end 54 of a sleeve 55 that is freely mounted upon the extreme lower end of the shaft 13. The sleeve 55 extends through an aperture in the cover plate 47 to receive thereon, below the plate, a contact arm 56 later to be described.

Secured to the lower face of the plate 47 is a block of molded insulating material 57 such as phenol condensate. The block 57 has formed therein a quarter-circular opening, the center of whose arcuate surface is in alignment with the shaft 13.

Attached to the arcuate surface of the block 57 are three arcuate parallel contactor strips 58, 59 and 60, each having a lug extension to receive a wire lead. As shown in Figure 11, the center contactor strip 59 is of greatest length, its opposite ends being formed inwardly to provide stops 61 and 62. The top contactor strip 58, which is shorter than the strip 59, is positioned with one end above the stop 62. The bottom contactor strip 60, which is the same length as the strip 58, is so positioned to bring its one end

in alignment with the stop 61. (See Figures 5, 6 and 11).

The contact arm 56 that engages the contactor strips 58, 59 and 60, will now be described. The arm 56 is formed to an open U shape, and is provided with oppositely disposed holes adjacent its closed end to receive therethrough the sleeve 55. In the center of the closed end of this U shaped arm 56 I have provided a threaded hole 63 to receive a set screw 64 by which the arm 56 is secured to the sleeve 55 in its adjusted position. (See Figure 6).

Between the open ends of the arm 56 I have pivotally mounted an elongated rocker arm 65 formed of molded insulating material.

Secured to the outer face of this rocker arm is a series of spaced contact fingers 66, one for each of the contactor strips 58, 59 and 60 and interconnected by a center strap 67. (See Figures 3, 6 and 11).

Each of the fingers 66 comprises an elongated yieldable, metal strip 68 whose outer free ends are curved to provide contact shoes 69 for smooth engagement with the contactor strips.

In the inner face of the rocker arm 65 I have provided an axial groove 70 to receive one end of a light, flat spring 71 whose opposite end fits in a like groove 72 milled in the wall of the sleeve 55. This spring 71 is made sufficiently long to provide a toggle action to quickly throw the rocker arm 65 to bring one or the other of the shoes 69 of the contact fingers out of engagement with the contactor strips. (See Figures 5, 6 and 11).

The function of the rocker arm will now be described in connection with the circuit employed. It is obvious that a person might close the electric circuit by pressing a button to cause the window to open, and unintentionally keep the circuit closed for a longer period of time than would be required to fully open the window with resulting damage to the motor or mechanism. In order to avoid such an accident I have provided automatic means to break the electrical circuit as soon as the window is fully opened or closed and locked.

Referring now to Figure 11, I have disclosed a conventional series motor 46 of the commutator type which is readily reversible on either alternating or direct current. I have also employed a conventional double pole, double throw switch 73, with modifications.

It is assumed that the window is closed and for the present the locking device will be ignored. The switch 73 is closed by pressing the button marked "Open" in Figure 10. Current will now flow from the mains to the motor field windings 74 and 75 through leads 74^a and 75^a, and from the field windings to the center terminals 76 and 77 of the switch 73 through leads 78 and 79. (See Figure 11). From the terminal 76 current will flow through one of the contact blades 80 to the contact 81, and thence through a lead 82 to one of the armature brushes 83. From the other terminal 77 current will flow through the contact blade 84 to the contact 85; thence through a lead 86 to the contactor strip 58. From the strip 58 current will flow to the strip 59 through the fingers 66; and then through a lead 87 to the armature brush 88. The motor will now start to rotate the quadrant shaft 13 to open the window.

When the window is fully opened, the contact arm 56 will strike the stop 61. As shown at Figure 6, the full line position of the finger 66 indi-

cates the position of the latter before striking the stop 61.

When the finger 66 engages the stop 61, the toggle spring 71 will throw the fingers 66 to the dotted line position in Figure 6, to quickly break the circuit between the center strap 59 and the end of the shorter top strap 58. The circuit, however, is immediately re-established between the center strap 59 and the lower strap 60, but 10 the motor is in-operative until the switch 73 is thrown to the opposite side.

The circuit used to close the window is similar to that previously described except that when the switch 73 is closed by pressing the button marked "Close" in Figure 10, current will flow from the strap 60 through a lead 89 to the terminal 90 on the switch 73, and from the terminal 81 through a short lead 91 to the remaining terminal 92 of the switch. When the window is 20 fully closed, the spring 32 will permit a further rotation of the quadrant shaft 13, and this additional travel after the window is closed is utilized to actuate the locking mechanism which will now be described.

Referring now to Figure 9, there is welded or otherwise secured to the inner face of the sash on the lock side, a U-shaped bar 93 to form between it and the face of the sash a vertical elongated opening 94. Secured to the inner face 30 of the mullion 1^a is a shallow channel member 95, extending the full height of the window and forming between it and the mullion an enclosed recess 96.

Slidably positioned within the recess 96 is a vertical bar 97 for each sash and formed with an offset upper end 98 that is adapted to be projected through a slot 99 in the side wall of the channel member 95. This offset upper end is provided with an inclined slot 100 that is adapted to receive a pin 101.

Now, when the bar 97 is drawn downwardly, the pin 101 will cam the offset end 98 outwardly through the slot 99 to enter the opening 94; and as a beveled face 102 on the offset end 98 is drawn into the opening 94, the window will be tightly closed.

To the lower end of the bar 97 there is pivotally connected one end of a bell crank 103, fulcrumed on a stud 104. To the other end of the crank 50 103 there is pivotally connected the outer end of an actuating rod 105. The rod 105 is formed to enter an aperture in the end wall of the housing 8; and within the latter, it is formed with an elongated slot 106 to receive a circular end 107 formed on the outer end of the locking pawl 28. (See Figure 4).

Between the shaft 13 and the outer end of the pawl 28, the latter has an arcuate slot 108 equal to the angular travel of the window and adapted 60 to receive therein a pin 109 projecting from the lower face of the gear quadrant 26. When the quadrant and the shaft 13 have been rotated sufficiently to close the window, the pin 109 will engage the end of the slot 108 and rotate the pawl 28. When the pawl 28 is rotated, its rounded end 107 that is received within the slot 106, will draw the rod 105 into the housing 8. When the rod 105 is thus moved axially the bar 97 will be drawn 65 downwardly to lock the window.

Surrounding the rod 105 adjacent the housing 8 is a helical compression spring 110 secured between an adjustable collar 111 on the rod and the housing 8. When the motor is operated to open the window, the first movement of the gear quadrant 26 will cause the pin 109 carried thereby to

release the pawl 28, and the compressed spring 110 will force the rod 105 from the housing 8 and also raise the bar 97 to unlock the window. At this time the teeth 29 on the collar 24 will engage the teeth 30 on the sleeve 31 and effect a positive drive to open the window. 5

In order to effect an emergency opening or closing of the window I have provided the following means. Projecting axially of the shaft 13, and through the hub of the handle 20, is a small bore 10 to slidably receive a pin 112 formed with a button head 113 where it projects above the handle 20. At its lower end, below the sleeve 31, the pin 112 engages a spring tensioned transverse key 114. This key is movable axially of the shaft 13 into 15 and out of engagement with a transverse keyway 115 formed in the lower face of the sleeve 31.

Normally the key 114 is held within the keyway 115 by a spring 116 below it to effect a driving connection between the sleeve 31 and the shaft 13. 20 However, when the button 113 above the handle 20 is depressed, the pin 112 will force the key 114 downwardly out of the keyway 115, and the shaft 13 may be freely rotated by the handle 20 to open and close the window. 25

After the button 113 is released, the spring 116 will force the key 114 into its keyway 115 when they are brought into registry by manually rotating the shaft.

In order that the window may be manually 30 unlocked to permit it to be manually opened, I have provided a finger grip 117 for the pin 101, where the latter extends through the face of the channel 95. When it is desired to unlock the window, the wings of the finger grip 117 are turned 35 to a vertical position and the pin 101 may be moved toward the center of the channel 95 to withdraw the offset end 98 from its locked position.

When the finger grip is in its normal position, 40 it is locked against lateral movement by its engagement with a rib 118 at the center of the channel 95.

I do not wish to be limited to the details of construction and arrangement herein shown and 45 described, and any changes or modifications may be made therein within the scope of the subjoined claims.

Having described my invention, I claim:

1. The combination with a stationary window 50 frame, a casement hingedly mounted therein for an outswinging movement, a housing connected to said frame, a vertical shaft rotatable in said housing, a connection between said shaft and the casement to swing the latter outwardly and inwardly when the shaft is rotated, a sleeve fixedly connected to said shaft, teeth on said sleeve, a second sleeve loosely fitted on said shaft, teeth on the second sleeve adapted to engage the teeth on the first sleeve to rotate the shaft to swing said casement outwardly, a motor connected to the second sleeve to rotate it in either direction, and a coil spring surrounding both sleeves and connected at one end to the first sleeve and at its other end to the second sleeve to provide a flexible 60 driving connection between said sleeves when the motor is operated to rotate the second sleeve in a reverse direction to swing the casement inwardly to a closed position. 65

2. The combination with a stationary window 70 frame, a casement hingedly mounted therein for an outswinging movement, a housing carried by said frame, a vertical shaft rotatable in said housing, a connection between said shaft and the casement to swing the latter outwardly or in- 75

- wardly when the shaft is rotated, means for rotating said shaft to swing said casement outwardly or inwardly, a shiftable device for unlocking and locking said casement, and a locking pawl rotatable by the shaft-rotating means, and operatively connected to the shiftable device, to draw the latter into locking engagement with the casement after it has been closed.
3. The combination with a stationary window frame, a casement hingedly mounted therein for an outswinging movement, a housing carried by said frame, a vertical shaft rotatable in said housing, a connection between said shaft and the casement to swing the latter outwardly or inwardly when the shaft is rotated, a horizontal shaft mounted in said housing, means for driving the horizontal shaft, a worm on said horizontal shaft, a quadrant connected to the vertical shaft, in mesh with said worm, a pawl freely mounted on the vertical shaft below the quadrant, and formed with an arcuate slot, a pin on the quadrant projecting into said slot, and a shiftable device for engaging said casement to lock it in a fully closed position, said device being operatively connected to said pawl, whereby, when the quadrant has been rotated sufficiently by the worm to close the casement, the pin will engage in the end of the slot in the pawl to rotate the latter to draw the shiftable device into locking engagement with the casement.
4. In combination, a stationary window frame, a casement vertically hinged thereon for an outswinging movement, a housing connected to said frame, a vertical shaft rotatable in said housing, an arm fixed on said shaft and slidably connected to said casement to swing the latter outwardly and inwardly as the shaft is rotated, a driving shaft rotatably mounted in said housing, a reversible electric motor for operating said driving shaft, means rotatably mounted on said vertical shaft and positively operated by said driving shaft and having an abutting portion for positively moving the vertical shaft in a direction to open the casement, a spring between said means and said vertical shaft for yieldingly driving said vertical shaft in a direction to close the casement, a shiftable device for locking and unlocking said casement with respect to said frame, and means operated by said driving shaft during initial starting and final stopping movements of the shaft when the casement is closed for moving said shiftable device to locking and unlocking positions.
5. In combination, a stationary window frame, a casement vertically hinged thereon for an outswinging movement, a housing connected to said frame, a vertical shaft rotatable in said housing, an arm fixed on said shaft and slidably connected to said casement to swing the latter outwardly and inwardly as the shaft is rotated, a driving shaft rotatably mounted in said housing, a reversible electric motor for operating said driving shaft, means operatively connected to the shiftable device for locking and unlocking said casement with respect to said frame, and means operated by said driving shaft during initial starting and final stopping movements of the shaft when the casement is closed for moving said shiftable device to locking and unlocking positions.
6. In combination, a stationary window frame, a casement vertically hinged thereon for an outswinging movement, a housing connected to said frame, a vertical shaft rotatable in said housing, an arm fixed on said shaft and slidably connected to said casement to swing the latter outwardly and inwardly as the shaft is rotated, a driving shaft rotatably mounted in said housing, a reversible electric motor for operating said driving shaft, means rotatably mounted on said vertical shaft and positively operated by said driving shaft and having an abutting portion for positively moving the vertical shaft in a direction to open the casement, a spring between said means and said vertical shaft for yieldingly driving said vertical shaft in a direction to close the casement, a shiftable device for locking and unlocking said casement with respect to said frame, and means operated by said driving shaft during initial starting and final stopping movements of the shaft when the casement is closed for moving said shiftable device to locking and unlocking positions, manually operable switch means for controlling the operation of said motor, and means for automatically stopping the motor when the casement is fully opened and when the shiftable device is in locking position.

RALPH W. CARNAHAN.
